UNITED STATES PATENT OFFICE

2,610,894

NURSING BOTTLE RINSER AND SPRAYER

Dianne Hall, Los Angeles, Calif.

Application October 22, 1948, Serial No. 55,915

2 Claims. (Cl. 299—83)

1

This invention appertains to novel and useful improvements in devices or apparatus for use in washing and rinsing baby nursing bottles.

An object of this invention is to introduce either plain water or water with a detergent therein into a number of bottles simultaneously for selective washing or rinsing purposes.

Another object of this invention is to selectively control the amount of detergent which is utilized by mere rotation of a valve member.

Another object of this invention is to supply an improved extension on the end of a number of tubes which extend from a water manifold or housing, which improved extensions have angularly disposed openings or apertures therein in order to introduce the liquid into the nursing bottles in a swirling pattern.

A still further object of this invention is to render cleaning a plurality of bottles a relatively simpler job, by introducing the detergent with the water directly into the bottle and by being able to wash one or more bottles simultaneously.

Ancillary objects and features of novelty such as simplicity of structure will become apparent to those skilled in the art, in following the description of the preferred forms of the invention, illustrated in the accompanying drawings, wherein:

Figure 1 is a perspective view showing one form of the invention in use;

Figure 2 is a partial sectional and partial elevational view of the housing and other associated mechanism;

Figure 3 is an enlarged elevational view of a tube extension, portions being broken away in section to illustrate details of construction;

Figure 4 is a sectional view taken on the line 4—4 of Figure 3 and in the direction of the arrows;

Figure 5 is a perspective view of a second form of the invention;

Figure 6 is a bottom view of the device;

Figure 7 is a top view of a valve control device for regulating the amount of detergent utilized;

Figure 8 is a sectional view illustrating the tube extension;

Figure 9 is a partial sectional and partial elevational view of the device illustrative of details of construction;

Figure 10 is a sectional view taken on the line 10—10 of Figure 9 and in the direction of the arrows;

Figure 11 is a sectional view illustrating details of construction taken on the line 11—11 of Figure 10 and in the direction of the arrows; and

2

Figure 12 is a sectional view somewhat similar to that shown in Figure 11, the two concentric tubes being disposed in a second operative position.

The specific structure of the present invention which is utilized for illustrative purposes may be seen by reference to the drawings as in two forms.

Referring to the first form, it is noted that a housing generally indicated at 10 is provided with a liquid inlet neck 12. This neck has an annular recess 14 extending therearound and a resilient collar 16 having its sleeve-like extension 18 disposed thereon. The said collar is maintained firmly in place through the utility of any suitable means, preferably the simply constructed resilient ring 20 which is disposed over the sleeve 18 and directly over the recess 14.

Means for detachably securing the collar 16 to a conventional water faucet 22 or other suitable equivalent water outlet means is provided. The preferable means consists of a number of annular ridges 24 or threads, which are disposed within the bore of the collar 16. It is quite apparent that the collar is simply pressed firmly onto the end of the faucet 22. Accordingly, it is equally as simple to remove the device, by performing the reverse operation.

A number of liquid outlet tubes 26 are disposed about the housing 10 or water manifold in radial fashion. These tubes have stems as at 28 for convenience and have extensions 30 disposed at the ends thereof.

The said extensions 30 have a number of angularly disposed outlet apertures therein which are utilized for the purpose of creating a swirling movement of water within the bottles 34, when they are disposed around the said extensions 30. This is, of course, how the washing and rinsing actually takes place.

A receptacle 36 forming means for retaining a detergent is provided. This receptacle has a reduced portion 38 at the open end thereof which is adapted to embrace the opening 40 at the bottom of the housing 10. Of course, the receptacle 36 may be knurled as at 42 for facility in rotating the same when rendering the bayonet latch generally indicated at 44, operative and inoperative. Through the utility of the bayonet latch the receptacle 36 may be readily applied and removed.

Attention is now directed to the embodiment of the invention shown in Figures 5—12. Here, a housing 50 is provided with a liquid inlet neck 52 having an enlarged roll 54 at the end there-

of. A collar 56 is disposed through the medium of its sleeve-like portion 58 on the said water inlet neck 52. It is seen that the enlarged portion 54 cooperates with the sleeve-like member 58 for detachably associating the collar 56 with the neck 52.

Means for retaining the collar 56 on a water faucet 22 or the like is provided. The preferable means is substantially identical to that shown in Figure 2, that is a number of annular ribs 60 are utilized. However, it is seen that a plenum chamber 62 is formed immediately below the annular ribs 60 and above the collar-like member 58.

Extending from the said housing 50 is a number of liquid outlet tubes 64. These liquid outlet tubes may be of resilient material in this instance, as may the tubes 28 in the species of the invention described hereinabove. In this instance the tubes 64 are operatively associated with the housing 50 by means of small pipe-like projections 66 which extend from the housing and have the tubes firmly disposed therearound.

At the opposite ends of the said tube 64 a number of extensions is provided. These extensions have a number of angularly inclined outlet openings 70 therein and in the bottom thereof in order to create a swirling motion of the liquid in the bottles 34 as it is introduced to the bottles 34.

An opening 72 is provided in the side of the housing 50. A closure for the opening is supplied and this closure is adapted to retain a detergent therein such as ordinary soap. The closure consists of a pair of concentric tubes 74 and 76 respectively which are rotatively mounted with respect to each other. Openings 78 are disposed in the outer sleeve or tube 74 while openings 80 are disposed in the inner sleeve. Accordingly, upon rotation of the tubes or sleeves with respect to each other, the effective size of the openings 78 and 80 cooperating with each other may be regulated. This permits more or less incoming liquid to come in contact with the detergent retained in the inner sleeve or tube 76.

Attention is now directed to Figure 10 wherein there is disclosed a pair of mating elements on the sleeves 74 and 76, one being a recess 84 while the other is a protuberance 86, both of annular configuration and provided about the respective peripheries of the sleeves. By the intermeshing of these two portions, rotative movement of the tubes or sleeves with respect to each other is permitted however, axial movement of one with respect to the other is prohibited.

In order to firmly attach the tubes in place on the housing 10 and within the opening 72, an internally threaded collar 88 is disposed on the end of the said tube 74. An externally threaded collar 90 is formed on the housing 10 adjacent the opening 72 and threadedly receives the threaded collar 88 thereon. A gasket 92 is interposed between this connection in order to make it substantially liquid tight.

The sleeve or tube 76 has a shoulder 96 at its upper end with thumb members 98 extending therefrom. Consequently, upon rotation of the thumb members, the tubes are rotated with respect to each other, thereby regulating the effective size of the openings 78 and 80 are described above. Noting Figure 5 it will be seen that in order to determine when the opening size is maximum and minimum, indicia such as "open" and "closed" may be supplied.

For filling the tube 76, the bore thereof may be threaded adjacent its end in order to detach-

ably receive a plug 100 therein. This plug of course is removed and detergent deposited or removed as it is found desirable.

In the operation of both forms of the invention, liquid is simply introduced into the housing or manifold and allowed to flow into the bottle. When it is desirable to rinse the bottles, in the second form of the invention the tubes are simply rotated in valve fashion to the selected position. In the first described form of the invention, the receptacle 36 is simply removed and detergent taken out, then replaced. Conversely, when it is desired to utilize the detergent, it is replaced. In the form of the invention shown in Figure 9 however, a simple manipulation of the thumb members 98 is all that is required for this operation.

It is within the purview of the present invention to utilize a plug in lieu of the sleeve arrangement shown in Figure 10 in order to close the opening 72. This is of course when only rinsing is desired, such as in large scale washing when there will be one device for rinsing and another utilized exclusively for cleaning. Nurseries, hospitals and the like would have occasion for such utility.

The following description has to do with the primary function of the two forms of the invention illustrated wherein each form is revealed to be in the nature of an attachment which is applied to the spigot or faucet and used in association with the regular sink. Thus applied as shown in Figs. 1 and 5, both attachments serve for both cleansing and rinsing nursing bottles or the like which are placed upright on the bottom of the sink. It is to be pointed out, however, that these attachments may have practical use in other ways. For instance, the respective containers may be charged with soluble or powdered soft drink. Thus each attachment may function as a mixer and distributor, filling a plurality of drinking glasses simultaneously. By the same token these attachments may be used on a shower pipe, that is as a substitute for a shower head or for either cleansing or rinsing purposes as the case may be. Using perfumed bath salts or soap compounds makes either device a handy contrivance for novel showering results.

While there has been described and illustrated but preferred forms of the invention, it is apparent that variations may be made without departing from the spirit thereof.

Having described the invention, what is claimed as new is:

1. An apparatus for washing a plurality of bottles comprising a housing having a longitudinal axis, a liquid inlet neck coaxial therewith, means for conducting liquid into said housing, said means comprising a flexible conductor, said neck having an annular groove therein, a resilient clamping ring encircling said conductor, pressing a portion of said conductor in said annular groove to thereby hold said conductor releasably on said neck, said housing having an open bottom, a flat bottomed imperforate detergent container having an open top with a peripheral recess thereon, the lower edge of said housing telescoping and being seated in said recess, means releasably connecting said container with its open top in communication with the open bottom of said housing, a plurality of tubes, said housing having openings in the sides thereof and said tubes being disposed in said openings, said tubes being arranged radially with respect to said axis, angular depending extensions disposed at

the outer ends of said tubes, said extensions defining liquid chambers and said extensions having discharge orifices therein for passage of liquid into upstanding bottles in which said extensions are adapted to be disposed.

2. For use with a kitchen sink and faucet combination, an attachment for the faucet comprising a cylindrical open bottomed hollow housing having a depending annular wall provided with a plurality of radial L-shaped tubes, said tubes being disposed in equi-distant circumferentially spaced relationship and embodying horizontal and vertical branches, said vertical branches terminating in perforated closed ended perforated extensions constituting spray nozzles, said housing being provided at its center with an upstanding water intake neck, means separably connected at one end with said neck and constituting a water intake conductor and being provided at its intake end with a collar which is frictionally attachable with said faucet, an imperforate flat bottomed internally unobstructed container attached to said housing and closing the open bot-

tom thereof, the vertical branches of said tubes depending below the bottom of said container.
